DESIGN FOR A DRESSER

George W. Harding, Baltimore, Md.

Application July 9, 1937, Serial No. 70,332

Term of patent 14 years

To all whom it may concern:

Be it known that I, George W. Harding, a citizen of the United States, residing at Baltimore, in the county of Baltimore and State of Maryland, have invented a new, original, and ornamental Design for a Dresser, of which the following is a specification, reference being had to the accompanying drawing, forming part hereof.

I claim:

The ornamental design for a dresser as shown.

GEORGE W. HARDING.
